WHEEL-MOUNT.

1,087,328.

Specification of Letters Patent.

Patented Feb. 17, 1914.

Application filed May 7, 1913. Serial No. 766,023.

To all whom it may concern:

Be it known that I, FELIKS SIWAK, a citizen of the United States, residing at Clifton Heights, in the county of Delaware and 5 State of Pennsylvania, have invented certain new and useful Improvements in Wheel-Mounts, of which the following is a specification.

My invention relates to improvements in 10 wheel mounts, and more particularly to an improved construction of pole which provides an improved mounting for a trolley wheel, allowing the trolley to swing and to move longitudinally with relation to the 15 pole, so as to easily follow all of the lines and curves of the wire without jumping therefrom.

A further object is to provide an improved device of this character which is 20 sensitive in its movements, so that it will be elastically held in contact with the wire at any position to which it may move, either laterally or longitudinally with relation to the pole to prevent the annoyance of the 25 wheel jumping from the wire, as well as prevent injury which frequently occurs from such cause.

With these and other objects in view, the invention consists in certain novel features 30 of construction and combinations and arrangements of parts as will be more fully hereinafter described and pointed out in the claims.

In the accompanying drawings: Figure 1 35 is a view in longitudinal section illustrating my improvements. Fig. 2 is a fragmentary rear view. Fig. 3 is a view in longitudinal section through the center of and at right angles to Fig. 1. Fig. 4 is a perspective 40 view of the removable back plate. Fig. 5 is a perspective view looking at the rear of the pole at its free or upper end, and Fig. 6 is a view in cross section on the line 6-6 of Fig. 1.

1 represents my improved trolley pole 45 which is provided near its upper or free end with a transverse recess 2 extending from side to side of the pole, and open to the rear of the pole. This recess 2 is connected by 50 a longitudinal groove 3 with a keystone shaped recess 4 below the said recess 2 and above the recess 2 the pole 1 has a longitudinal recess 5 with rearwardly projecting ears 6, 6, at opposite sides thereof. These 55 ears 6, 6, have beveled or inclined ends 7,

and the said recesses 5 and 4 and groove 3 conform in shape to enlargements 8, 9, and 10 respectively, integral with a rear plate 11, so that when the latter is assembled, against the rear face of pole 1, the several 60 enlargements and recesses form a firm interlock preventing any possibility of lateral displacement of the plate. The enlargement 8, at its lower wider end, is formed with a curved slot 12 concentric with a pivot pin 65 13 which projects through the plate 11, enlargement 8, and pole 1, and is secured in any approved manner.

A trolley fork 15 supports a trolley wheel 16 at one end, and between its ends is provided with a slot 17 receiving the pin 13. The inner end of this trolley fork 15 is provided with a curved segment 18 which is adapted to swing in the arc of a circle and against this segment 18, a block 19 is held 70 by means of a coiled spring 20. A rod 21 secured to block 19 extends through a guide plate 22 into a pocket 23 in pole 1, and the spring 20 is located between the guide plate 22 and the block 19 to always press the latter against the segment 18. By reason of the slot 17, the trolley fork 15 is permitted 75 longitudinal movement as well as lateral swinging movement, so that the trolley wheel 16 can follow all of the varying positions of the trolley wire 24 without jumping therefrom.

Pins 25 are projected through openings 26 in the plate 11, and through openings 27 in pole 1, and are secured by cotter pins 28. 90 These pins 25 are grooved in their heads 29, and in said grooved heads, a flat spring 30 is secured. The free end of this flat spring 30 projects through a staple 31 secured to segment 18 and projecting through the 95 curved slot 12 in plate 11. The spring 30 therefore tends to maintain the trolley fork 15 in normal position and return it to such position when swung laterally, while the spring 20 exerts a longitudinal pressure on 100 the fork 15 and normally holds the latter in its operative position, yet allows the same to be moved in the opposite direction to compensate for various positions of the wire.

To strengthen the connection between the fork and the pole, I provide a U-shaped strap 32 which is located in a recess 33 in enlargement 8, and through which strap the pivot pin 13 above referred to is positioned. 110

The ends of this strap 32 extend around the sides of the pole and through a cross bar 33^a, said cross bar located against the front or upper face of the trolley pole and the intermediate portion of said strap 32, located in recesses 34 in enlargement 7. The ends of the strap may, of course, be secured in various ways, and I have illustrated for the purpose, nuts 35 screwed onto the ends 10 of the straps and against the bar 33.

To limit the outward movement of the fork 15, a shoulder 36 is provided on the inner end thereof which rides against a curved wall 37 on pole 1.

15 Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure 25 by Letters Patent is:

1. The combination with a pole, of a fork having slot and pin connection between its ends with the pole, a wheel carried by the outer end of said fork, a segment on the 30 inner end of said fork, elastic means pressing against said segment, and a spring secured to the pole and connected to the segment, substantially as described.

2. The combination with a pole, of a fork 35 having slot and pin connection between its ends with the pole, a wheel carried by the outer end of said fork, a curved segment on the inner end of said fork, a spring-pressed block bearing against the segment, and a 40 straight spring secured to the pole and connected to the segment, substantially as described.

3. The combination with a pole having recesses therein at its free end on its rear

face, of a plate covering said recesses and 45 having a curved slot therein, a pivot pin projecting through the plate and pole at its free end, a trolley fork having a longitudinal slot therein through which said pin is projected, a wheel carried by the free end 50 of said fork, a curved segment on the inner end of said fork, a spring-pressed device engaging the segment and exerting outward pressure thereupon, a straight spring secured to the pole, and a device on the segment projecting through the slot in the plate and through which device said last-mentioned spring is projected, substantially as 55 described.

4. The combination with a trolley pole 60 having recesses in its rear face, of a longitudinally and laterally swinging trolley fork mounted in said recesses, a spring exerting outward pressure on said trolley fork, a second spring tending to center the trolley 65 fork with relation to the pole, and pins projected through the plate and the pole, and to which said last-mentioned spring is secured, substantially as described.

5. The combination with a trolley pole 70 having recesses in its rear face, of a longitudinally and laterally swinging trolley fork mounted in said recesses, a spring exerting outward pressure on said trolley fork, a second spring tending to center the trolley 75 fork with relation to the pole, pins projected through the plate and the pole, and to which said last-mentioned spring is secured, and a U-shaped strap positioned around the fork and pole, substantially as described. 80

In testimony whereof I have signed my name to this specification in the presence of two subscribing witnesses.

FELIKS SIWAK.
